(51) **LOC (14) Cl.** **28-03**

CLAIM

(52) **U.S. Cl.**

The ornamental design for a sperm sampler, as shown and
described.

USPC **D24/215**

DESCRIPTION

(58) **Field of Classification Search**

1. Sperm sampler
- 1.1 Front view;
- 1.2 Back view;
- 1.3 Left view;
- 1.4 Right view;
- 1.5 Top view;
- 1.6 Bottom view; and
- 1.7 Perspective view.
